CURRENT METERING SYSTEM

Frank G. Kear, Minersville, Pa., assignor to Washington Institute of Technology, Inc., Washington, D. C., a corporation of Delaware

Application February 26, 1937, Serial No. 128,037

2 Claims. (Cl. 171—229)

This invention relates to electrical systems in which two or more loads, such as antennas, are energized from a common source of power and in which it is desired to establish a desired phase and magnitude relationship between the currents in the loads and to control the power supplied to the loads.

It has been found, particularly in adjusting antenna circuits to secure desired relationships of the phase and magnitude of the currents therein, that the current relationships, with respect to either phase or magnitude, cannot be established by simple means. This is due to various conditions, among which is the fact that at the frequencies usually employed in radio broadcasting, the input transformers supplying the antennas do not act as simple transformers, due to leakage flux or distributed capacity between the turns of one winding or between the turns of the two windings. Further, the antennas themselves cannot be accurately tuned because of slight differences in radiation characteristics between antennas in a given array. Heretofore a pre-determined current relationship has been secured, or approximated, in a given array by adjusting the tuning of one or more of the antennas or the circuits which supply the antennas by trial and error methods. This has proved to be an entirely unsatisfactory procedure because of the fact that the antenna currents involve two variable factors which are mutually interdependent, i. e. the phase and amplitude factors. Thus, it has been found that in tuning one antenna of an array in order to produce a desired amplitude relationship, the phase relationship of the antenna currents is changed, while if an initial adjustment of phase relationship is made the amplitude relations of the currents are disturbed. The problems involved in tuning by trial and error methods are accentuated if more than two antennas or loads are to be adjusted to a desired current relationship, as it will be apparent that the possible variations of phase or amplitude of the antenna currents will increase with the number of antennas in the array.

The present invention has for its principal object the provision of a method of tuning any number of antennas which form an array, by which method either the phase or the amplitude of the current in an antenna or load may be varied without causing a similar or other variation in the other factor of the current.

The method according to this invention also has for an object to provide a means for securing any desired phase and magnitude relationship between the currents in interconnected circuit elements, such as antennas.

It is also an object of the invention to provide apparatus which may be employed in carrying out the method according to the invention.

Referring to the drawing, wherein similar reference characters refer to like parts,

Fig. 1 is a diagram of a circuit which is particularly adapted for the energization of two loads.

Fig. 2 is a diagram of a circuit which may be employed for energizing three loads;

Fig. 3 is a circuit diagram showing a practical embodiment of the circuit disclosed in Fig. 2;

Fig. 4 is a diagram showing a balanced-to-ground circuit for energizing two loads, and

Fig. 5 is a diagram of a circuit which is similar to that disclosed in Fig. 2, but in which the antenna currents are adjusted to different values.

According to the present invention, the amplitude and phase relationships of the currents in two or more antennas or other circuit elements may be adjusted by a procedure which involves the connection in series with one of the loads, of an impedance, which may be either inductive or capacitative in character and which is of such magnitude as to cause the impedances in the circuit, when arranged and considered in a pre-determined manner, to become equivalent to the desired current relationship. The method may be best understood by reference to an actual example.

In Fig. 1 there is disclosed a circuit which is designed for the energization of two antennas or loads which are represented by the impedances Z_1 and Z_2 and in which loads, respectively, are flowing the currents I_1 and I_2 in the directions shown by the arrows. The impedance Z_1 is connected in parallel with two series-connected voltage-dividing impedances Z_3 and Z_4 , the outer terminals of which are connected to the terminals of the secondary of an input transformer T , which delivers alternating current at voltage E , and in which impedances respectively, are flowing the currents I_3 and I_4 . One terminal of the load Z_2 is connected to the connection between impedances Z_3 and Z_4 , the other terminal of load Z_2 being so connected that load Z_2 is in parallel with either impedance Z_3 or Z_4 , it being shown in Fig. 1 as being so connected to impedance Z_4 . The impedances Z_3 and Z_4 may be either inductive or capacitative in character.

An examination of the circuit disclosed in Fig. 1 shows that certain relationships exist between the voltages, currents and impedances of the elements thereof. Certain of these relationships are of importance in the method according to this invention, and are as follows:

$$I_1 = \frac{E}{Z_1 + X}$$

in which X is an impedance which may be connected in series with load Z_1 , in a manner and for a purpose to be set forth hereinafter. In as-

much as the voltage E divides between impedances Z_3 and Z_4 ,

$$E = Z_3 I_3 + Z_4 I_4$$

and, inasmuch as the voltage across impedance Z_4 is equal to that across impedance Z_2 ,

$$Z_2 I_2 = Z_4 I_4 \text{ and } I_4 = \frac{Z_2 I_2}{Z_4}$$

and

$$I_3 = I_2 + I_4$$

$$Z_2 I_2 = Z_3 (I_2 + I_4) = Z_3 I_2 + Z_3 I_4$$

and

$$E = Z_3 I_2 + Z_3 I_4 + Z_4 I_4$$

$$= Z_3 I_2 + Z_3 \left(\frac{Z_2 I_2}{Z_4} \right) + Z_4 \left(\frac{Z_2 I_2}{Z_4} \right)$$

$$= Z_3 I_2 + \frac{Z_3 Z_2}{Z_4} I_2 + \frac{Z_4 Z_2}{Z_4} I_2$$

$$= \left(Z_3 + Z_4 + \frac{Z_3 Z_2}{Z_4} \right) I_2$$

and

$$I_2 = \frac{E}{Z_3 + \frac{Z_3 Z_2}{Z_4} Z_2 + Z_2}$$

and since

$$I_1 = \frac{E}{Z_1 + X}$$

$$I_1 = \frac{Z_2 + \frac{Z_3}{Z_4} Z_2 + Z_3}{Z_1} \quad (1)$$

when

$$X = 0$$

It will be seen that I have derived an expression for the relationship of the currents in two loads, which is expressed entirely in terms of the impedances of the circuit in which the loads are connected, and from which any pre-determined ratio of currents may be readily obtained by adjustment of the impedances Z_3 and Z_4 .

The current ratio expression (1) as set forth above may be rewritten as follows:

$$I_1 = \frac{Z_2 \left(1 + \frac{Z_3}{Z_4} \right) + Z_3}{Z_1}$$

It will be apparent that if the values of Z_3 and Z_4 are expressed by imaginary numbers then the ratio

$$\frac{Z_3}{Z_4}$$

will be a real number and the value of this ratio must first be ascertained in carrying out the method according to this invention.

If it be assumed that the loads Z_1 and Z_2 are to be so adjusted that the current I_1 will be three times the current I_2 , then

$$I_1 = 3 = \frac{Z_2 \left(1 + \frac{Z_3}{Z_4} \right) + Z_3}{Z_1}$$

For the purpose of determining the value of the ratio

$$\frac{Z_3}{Z_4}$$

the single term Z_3 of the numerator of expression (1) may be disregarded, and the foregoing equation may be rewritten as follows:

$$I_1 = 3 = \frac{Z_2 \left(1 + \frac{Z_3}{Z_4} \right)}{Z_1} \quad (2)$$

The impedances Z_1 and Z_2 may be measured by any known means and it will be assumed that, in the present case, these impedances are 75 ohms and 50 ohms respectively. If these values are

substituted in Equation 2 the value of the ratio

$$\frac{Z_3}{Z_4}$$

may be found by solving the equation, in the following manner:

$$3 = \frac{50}{75} \left(1 + \frac{Z_3}{Z_4} \right)$$

$$9 = 2 + 2 \frac{Z_3}{Z_4}$$

$$\frac{Z_3}{Z_4} = \frac{7}{2}$$

The known values may now be substituted back into Equation 1, giving

$$\frac{I_1}{I_2} = 3 = \frac{50 \left(1 + \frac{7}{2} \right) + Z_3}{75} \quad (3)$$

It will be seen that a lack of equality exists between the two sides of relation (3), this inequality being represented by the term Z_3 . If the equation in its present form should be solved for Z_3 , this term would have a value of zero. It is known, however, that neither Z_3 or Z_4 are of zero value but, on the contrary, have measurable values which are related in accordance with the ratio

$$\frac{Z_3}{Z_4} = \frac{7}{2}$$

If a value of $-j50$ ohms is assumed for Z_4 , this impedance may actually be adjusted to that value although an inductive element may be employed. This will give for Z_3 the value of $-j175$ ohms and this impedance may actually be given that value. The relation (3) may now be rewritten as

$$\frac{I_1}{I_2} = 3 = \frac{50 \left(1 + \frac{7}{2} \right) - j175}{75}$$

It will be seen again that a lack of equality exists between the two elements of this relation, such inequality being represented by the term $-j175$. In order to bring the two terms of the relation into equality, a term must be added to the denominator of the right hand term of the relation, which term may be denoted X , as follows:

$$\frac{I_1}{I_2} = 3 = \frac{50 \left(1 + \frac{7}{2} \right) - j175}{75 - X}$$

The value of the term X must be so related to the value of the term Z_3 as to maintain the pre-determined relationship between the numerator and denominator of the right-hand item. In the present example the value of X must obviously be one-third the value of the term Z_3 in order to make the fraction equal to 3. In other words, the value of X in the present example is 58%.

The value of the term X measures the value of an added impedance X which is inserted into the circuit in series with the impedance Z_1 . It will be seen that the denominator of the right-hand term of the equation has been so changed that the term Z_1 has become $Z_1 + X$ and this change is given effect in the circuit by inserting the added impedance in the described manner. The addition of the impedance X causes the desired current relationship P to be secured, with respect to both the phase and magnitude of the currents in the loads.

30

40

45

50

55

60

70

75

In the general case, the equation may be written

$$\frac{I_1}{I_2} = P = \frac{Z_1 \left(1 + \frac{Z_3}{Z_4}\right) + Z_5}{Z_1 + X}$$

and

$$X = \frac{Z_3}{\text{Current ratio}}$$

- 10 According to the method described it will be seen that the desired phase and amplitude relationship between the currents in the two interconnected circuit elements is secured by increasing the impedance of the circuit containing the load Z_1 by an amount which may be easily calculated after the values of the voltage-dividing impedances have been determined. In practise this is effected by inserting the impedance X in the circuit containing load impedance Z_1 and in series with the load impedance, this being diagrammatically illustrated in Fig. 1. If the value of the impedance X is properly chosen in the manner described, the desired phase and amplitude relation between the currents in the loads Z_1 and Z_2 will be achieved without the necessity of resorting to trial and error methods. It will be apparent that impedance X may be either inductive or capacitative in character, but must be the same in character as Z_3 .
- 30 If the value of impedance Z_3 is much less than the line impedance, the ratio

$$\frac{Z_1}{Z_4}$$

- 35 is dependent upon the load to the extent that the voltages in the loads remain in phase. This may be illustrated as follows:

Across load Z_2 there exists the voltage

$$E_{Z_2} = \frac{Z_{15}}{Z_1 + \frac{Z_3}{Z_4} Z_1 + Z_5}$$

$$E_{Z_2} = \frac{E}{\left(1 + \frac{Z_3}{Z_4}\right) + \frac{Z_5}{Z_1}}$$

and

$$E_{Z_1} = E$$

If the value of the ratio

$$\frac{Z_1}{Z_4}$$

is much less than one then the ratio

$$E_{Z_1}/E_{Z_2}$$

- 55 is independent of the character of the load Z_2 . This condition is necessary in order that the transmission lines synchronize with the load Z_1 . It is noted that this discussion is not essential in the method of establishing current ratios according to the present invention, but is useful if a phase synchronization network is employed.

- 60 In Fig. 2 of the drawing there is disclosed a circuit embodying and employing the principles of the present invention and in which three equal loads Z_1 , Z_2 and Z_5 are arranged, the connection of these loads being such that the currents I_1 , I_2 and I_5 flowing therein will have the relationship

$$I_2 = I_5 = nI_1$$

- 65 In order to achieve equality between the currents I_2 and I_5 , flowing in loads Z_2 and Z_5 respectively, these two loads are connected in parallel and are 70 both connected in parallel with one of the two

voltage-dividing impedances Z_3 , Z_4 which are connected in series and are both connected in parallel with the load Z_1 .

In this particular case the current relationship

$$I_1 = I_2 + I_5$$

will obtain, inasmuch as the loads Z_2 and Z_5 are to be so adjusted that the currents flowing therein are equal. The total impedance of the circuit including loads Z_2 and Z_5 is measured and this 10 value is taken as the value of the term Z_2 of the expression (1). If the current in load Z_1 is to be twice that in either of loads Z_2 and Z_5 , then it may be assumed that, when the impedances of these loads are measured the load Z_1 is found 16 to have an impedance of 100 ohms, while the total impedance of the circuit containing loads Z_2 and Z_5 is 50 ohms. The values of the impedances Z_3 and Z_4 may be assumed as

$$Z_3 = Z_4 = -j25$$

Then

$$\frac{I_1}{I_2 + I_5} = 1 = \frac{Z_3 + \frac{Z_3}{Z_4} Z_2 + Z_5}{Z_1}$$

$$= \frac{50 + 50 + (-j25)}{100}$$

In order to bring this relation into equality, an additional term must be added to the denominator of the right-hand expression and this added term will, in the present example, be equal to Z_3 in order to maintain the correct and pre-determined relation between the numerator and denominator. The equation now becomes

$$\frac{I_1}{I_2 + I_5} = 1 = \frac{100 - j25}{100 + X}$$

or

$$\frac{I_1}{I_2 + I_5} = 1 = \frac{100 - j25}{100 - j25}$$

In order to embody the effect of the added term X in the actual circuit, the added impedance X is inserted in the circuit in series with impedance Z_1 , this added impedance having the value determined above. When this is done, the currents in loads Z_1 , Z_2 and Z_5 will have the desired phase and magnitude relationships.

The relationship of the voltages in this circuit may be shown to be

$$\frac{E_1}{E_2} = \frac{Z_3 + \frac{Z_3}{Z_4} Z_2 + Z_5}{Z_1}$$

$$= \frac{-j25 + \frac{-j25}{-j25} 50 + 50}{50}$$

$$= \frac{-j25}{50} + 1 + 1$$

$$= 2 - j0.5$$

From this it will be seen that only the imaginary values of circuit elements will change with any change in Z_2 and that good control will therefore be secured. The degree of control over phase and magnitude relations of the currents in the loads may be improved by choosing smaller values for Z_3 and Z_4 . This particular discussion is of importance only in securing phase control.

The circuit disclosed in Fig. 2 is particularly 70 designed for the energization of loads in which the current relationship

$$I_2 = I_5 = nI_1$$

is to be obtained. If an unequal relationship 75

between the currents in all of the loads is to be secured the circuit disclosed in Fig. 5 may be employed. In this circuit arrangement one of the loads such as Z_5 is connected in parallel with one of the voltage-dividing impedances, such as Z_4 . Also connected in parallel with the impedance Z_4 are two series-connected impedances Z_6 and Z_7 . The load Z_2 is connected in parallel with one of the voltage-dividing impedances Z_6 , Z_7 , and is shown so connected with impedance Z_7 . The desired relationship between the phase and magnitude of the currents I_1 and I_2 , flowing in loads Z_1 and Z_2 , respectively, may now be secured by the method described. The ratio

15

$$\frac{Z_3}{Z_4}$$

must first be determined and from this the value of Z_3 may be computed after assigning a chosen value to Z_4 . These values may now be substituted back into Equation 1 in order to determine the quantity which must be added to the denominator in order to secure equality between the terms of the equation, this quantity measuring the value of the impedance X which is to be connected in series with load Z_1 in order to secure the proper relation of phase and magnitude between the currents in loads Z_1 and Z_5 .

30 The desired relationship between the currents in loads Z_1 and Z_5 having been secured, the voltage across impedances Z_6 and Z_7 will be known and will be equal to the voltage across load Z_5 . The desired relationship between the currents in loads Z_2 and Z_5 may now be secured by the method according to the invention, the impedance X_A being connected in series with load Z_5 and having a value determined by the quantity added to the denominator of the right hand term of Equation 1 in order to make such equation a true equality. In this manner the desired relationship between the currents in loads Z_2 and Z_5 may be secured and inasmuch as the desired relationship between the currents in loads Z_1 and Z_5 had already been secured, it will be seen that the three loads have been adjusted in the predetermined manner.

35 In Fig. 3 of the drawing there is disclosed a circuit in which the invention is applied to the energization of three transmission lines, the connections being as actually made in practice. The transmitter, which is disclosed in the drawing, supplies current at radio frequency to two leads A and B, across which are connected the two series-connected voltage-dividing impedances Z_3 and Z_4 . One of the output leads, such as A, is connected directly to a transmission line 1, the same having an impedance Z_1 . Two transmission lines 5 and 6, having impedances Z_5 and Z_6 respectively, are connected in parallel and to the common connection between impedances Z_3 and Z_4 . The method according to this invention is employed to determine the value of the impedance X which is connected in series with the load Z_1 in order to secure the desired phase and magnitude relationship between the currents in the three loads. In the case illustrated in Fig. 3 the currents I_1 and I_2 , flowing in loads Z_1 and Z_5 respectively, are intended to be equal. If such a relationship is not desired the means illustrated in Fig. 5 may be employed and a second added impedance, corresponding to impedance X_A of Fig. 5, must be added to either of loads Z_5 or Z_6 in order to secure the desired relationship between the currents in these loads.

40 In Fig. 4 of the drawing there is disclosed a circuit for so energizing two loads that they will be in phase with respect to each other and balanced with respect to ground. In this circuit the load Z_1 is connected across the terminals of the secondary of the input transformer. Connected in parallel with load Z_1 and also across the terminals of the secondary of the input transformer are three series-connected impedances 4, 5 and 6 having the values

$$\frac{Z_3}{2}, Z_4 \text{ and } \frac{Z_3}{2}$$

45 respectively. The load Z_2 is connected in parallel with the impedance Z_4 . As in other cases, the method according to this invention is employed in order to determine the value of the added impedance which must be connected in series with the load Z_1 , in order to secure the desired phase and magnitude relation between the currents in the loads Z_1 and Z_2 . In the present case, however, this added impedance is divided equally and two impedances X_1 and X_2 , which are equal in value, are connected in series with the load Z_1 , one of these added impedances being connected in each branch of the circuit including load Z_1 , as clearly illustrated in Fig. 4.

50 I have provided, by the present invention a simple and easily practised method of adjusting the currents in two or more interconnected circuit elements to a pre-determined relationship with respect to both phase and magnitude. I have disclosed, in this application, certain circuits illustrating the application of the invention and how the invention may be practised in certain specific cases. It is to be clearly understood, however, that the invention is not limited in any way by the description and drawing of this application, and that the scope of the invention must be sought in the appended claims.

40 I claim:

1. An electrical system comprising a source of power and a plurality of load devices connected to said source to be energized thereby, means for producing a pre-determined phase and magnitude relationship between the currents in said load devices, said means comprising a plurality of series-connected impedances connected across the output of said source, one of said load devices being connected in parallel with said impedances, another of said load devices being connected in parallel with one of said impedances, and a compensating impedance connected in series with said first-named load device and having the value Z_3/P , in which Z_3 is the impedance of that portion of the series-connected impedances which is not in parallel with said second load device.

55 2. An electrical system for producing a pre-determined phase and magnitude relationship P between currents in connected load devices which are energized by a common source of power and which have impedances Z_1 and Z_2 respectively, comprising series-connected impedances Z_3 and Z_4 connected across the output of said source and in parallel with one of said load devices Z_1 , said impedance Z_4 being connected in parallel with the second of said load devices Z_2 , and a compensating impedance X connected in series to said load device Z_1 and having the value

$$X = \frac{Z_2 \left(1 + \frac{Z_3}{Z_4} \right) + Z_3 - PZ_1}{P}$$
